UNITED STATES PATENT OFFICE.

CLIFFORD C. BROOKS AND EDWIN O. KLEMM, OF FENTON, MICHIGAN, ASSIGNEES TO
KLEMM MANUFACTURING COMPANY, OF FENTON, MICHIGAN, A CORPORATION OF
MICHIGAN.

AUTOMATIC GRAPHOPHONE STOP.

Application filed October 14, 1922. Serial No. 594,610.

To all whom it may concern:

Be it known that CLIFFORD C. BROOKS and EDWIN O. KLEMM, citizens of the United States, residing at Fenton, in the county of Genesee and State of Michigan, have invented certain new and useful Improvements in Automatic Graphophone Stops, of which the following is a specification.

The present invention relates in general to a control device for phonographs and like machines, and more particularly to a novel mechanism whereby the operation of the phonograph may be automatically stopped when the reproducer reaches the end of the record, or any other predetermined point upon the record which may be selected by the operator.

Quite a number of phonograph stop devices have been developed, although they are largely open to the objection that it is difficult or impossible to set them with any degree of accuracy, the common complaint being that the automatic stop either functions too soon or too late or not at all. With many of the stops the construction is such that in the preliminary setting of the device the tone arm must be moved in a certain particular direction, and the instructions frequently specify that the reproducer shall be moved a number of grooves beyond the point where it is desired to stop the playing of the machine. These are all features which tend to result in confusion on the part of the operator and inaccuracy in the operation of the stop.

With the foregoing considerations in view one of the objects of the present invention has been to provide a phonograph stop which embodies novel features of construction whereby it can be accurately set with ease and facility, and in which it is not necessary to move the tone arm in some particular direction when setting the device preparatory to rendition of the record.

Further objects of the invention are to provide a device of this character, which is extremely simple and inexpensive in its construction, which can be applied without difficulty to any of the conventional types of phonographs now found upon the market, and which is positive and dependable in its action.

While certain particular embodiments of the invention have been illustrated and described for the purpose of explaining the idea, it will be understood that numerous modifications and changes are possible in the details of construction without departing from the spirit of the invention.

For a full understanding of the invention reference is to be had to the following description and accompanying drawings, in which:

Figure 1 is a plan view of a fragmentary portion of a phonograph with one of the automatic stop devices applied thereto, portions being broken away and shown in section.

Figure 2 is a side elevation of the parts shown by Figure 1, the detent and brake member being shown by full lines in inoperative position and by dotted lines in operative position.

Figures 3 and 4 are detail views illustrating a modification which is adapted to be used for controlling electrically driven machines.

Figure 5 is a side elevation showing one of the devices as applied to a Victor type of tone arm, the brake member being shown in operative position by full lines and in inoperative position by dotted lines.

Figure 6 is a perspective view showing a modification in which a gravity controlled brake operating lever is utilized.

Figures 7 and 8 are detail views showing different forms of pivotal connections between the trip arm and the bracket at the base of the tone arm.

Figure 9 is a detail view illustrating a modified form of detent member.

Corresponding and like parts are referred to in the following description, and illustrated on all of the views of the drawings by like reference characters.

The embodiments of the present invention which have been shown for illustrative purposes can be applied as an attachment to many of the conventional types of phonographs which are now upon the market, the invention being illustrated by Figures 1 and 2 as utilized in connection with tone arms which are known as the Columbia type and have a universal movement at their base,

while on Figure 5 the device is shown as applied to a phonograph having a tone arm of the Victor type.

Referring to Figures 1 and 2 of the drawings, the reference character A designates a tone arm which has the conventional universal joint B at its base so that it is adapted to swing both horizontally and up and down. A conventional reproducer C is mounted upon the swinging end of the tone arm, said reproducer carrying the usual needle which is adapted to operate within the grooves of the record D. The turn table E which carries the record is mounted upon a spindle F and may be driven in any suitable manner, either by a spring motor or by an electric motor. The top of the phonograph is illustrated at G. This is all of the conventional and well known construction and no claim 20 to novelty is based thereon.

The numeral 1 designates a control lever, which is provided with pivot members 2, by means of which it is mounted upon up-standing ears 3 projecting from a base plate 4. The control lever may be conveniently formed from a plate stamped from sheet material of a suitable gauge, and the portion of the lever which is provided with the pivot members 2 is preferably widened so that the pivot members are an appreciable distance apart. This tends to prevent lateral play or movement of the control lever, and is conducive to accuracy in the operation of the device. The base plate 4 is adapted to be mounted on the top G of the phonograph cabinet, and it may be secured in position in any suitable manner as by means of the screws 5. The inner end of the control lever 1 terminates in a comparatively thin arm 1^a which is returned upwardly and carries a brake shoe 6 which is adapted to engage the bottom of the turn table E. The returned arm preferably extends outwardly beyond the axis of the lever, so that the brake shoe 6 is moved upwardly into operative engagement with the turn table when the outer end of the control lever is swung upwardly, and is correspondingly swung downwardly to release the turn table when the outer end of the control lever is swung downwardly.

The outer end of the control lever is provided with an upstanding wing or detent 7, which is transversely disposed with respect to the lever, said detent member being provided at its top with a riding edge 7^a and with a notch 8 at one end of the riding edge, a stop arm 9 projecting upwardly at the side of the notch remote from the riding edge. A spring 10 engages the control lever and normally tends to swing the same into operative position, said spring being shown as having one end thereof connected to the returned portion of the control lever arm 1^a, and the other end thereof connected to a lip 11 which is cut from one edge of the base

plate 4 and bent upwardly therefrom. This is preferably a light spring and one which has just sufficient strength to apply the brake in the necessary manner to stop the machine when the control lever is released. 70

Cooperating with the riding edge 7^a and notch 8 of the detent member 7 is a trip arm 12, which is carried by and movable with the tone arm, said trip arm being adapted to frictionally engage and ride upon the edge 7^a of the detent member and to enter the notch 8 of the detent member when it is brought into registry therewith. The width of the trip arm corresponds accurately with the width of the notch 8, so that there is 80 practically no lateral play when the arm is received within the notch. In other words, the arm has what may be termed a sliding fit within the notch, and, as will be hereinafter explained, this is conducive to great accuracy in the preliminary setting of the stop device. The trip arm is carried by a bracket 13, which is secured to one side of the tone arm A at the base thereof. This bracket is illustrated as having an L shaped formation, 90 one arm thereof being secured to the tone arm by a suitable fastening member 14, while the opposite arm thereof projects outwardly from the tone arm and has a frictional engagement with the trip arm 12. 95 The trip arm normally moves with the tone arm, although it is susceptible of an independent movement when a sufficient amount of force is applied thereto to overcome the frictional engagement between the trip arm 100 and the bracket. In this manner provision is made for the initial setting of the stop device.

The trip arm 12 is shown as having the pivot end thereof returned at 12^a, said returned portion embracing the outstanding arm of the bracket 13 and having an inherent resiliency which assists in obtaining the desired frictional contact at the pivotal connection between the members. This pivotal connection may be accomplished in many different ways, and for illustrative purposes two satisfactory forms of pivot joints are shown by Figures 7 and 8. In Figure 8 a screw 15 is threaded in the returned arm 12^a 115 of the trip member and provided at its inner end with a recess to receive a ball 16 which is in turn seated within a corresponding recess in the bracket 13. The resiliency of the returned arm 12^a enables the screw to be 120 tightened to obtain the desired frictional engagement at the pivotal connection of the parts, and a jam nut 17 can then be screwed down to lock the parts in an adjusted position. A slightly different construction is 125 illustrated by Figure 8, in which the screw 15^a terminates in a frusto conical end which engages a flared seat in the bracket 13 and cooperates therewith to produce the desired frictional engagement between the parts. 130

The trip arm thus swings normally with the tone arm, although it is susceptible of being moved independently thereof in the preliminary setting of the mechanism.

- 5 When preliminarily setting the device the trip arm 12 is engaged in the notch 8 and the tone arm then moved until the reproducer is at that point on the record where it is desired to stop the phonograph and discontinue 70 operation thereof. Owing to the fact that the arm 12 has a sliding fit in the notch 8, it will be obvious that the tone arm can be moved in either direction when making this preliminary adjustment, since it is immaterial which side of the notch is engaged by the trip 12, and there is not an appreciable amount of play of the trip member within the notch. When the trip 12 is positioned within the notch the control lever 1 is swung into operative position by the action of the spring 10, thereby holding the 75 brake shoe in engagement with the turn table. After this preliminary adjustment the tone arm is lifted and moved to its starting point upon the record. When the tone arm is lowered to bring the reproducer into operative engagement with the record the trip member 12 engages the riding edge 7^a of the 80 detent member 7 and bears downwardly thereon, to swing the control lever against the action of the spring 10 and disengage the brake shoe from the turn table. This sets the machine in operation and the trip arm remains in a sliding engagement with the riding edge and cooperates therewith to hold the control lever in 85 inoperative position until the reproducer reaches that point on the record at which the mechanism has been set to discontinue 90 the operation of the machine. The trip arm 12 is then in registry with the notch 8 and the control lever 1 is immediately actuated by the spring 10 to bring the brake shoe 6 into engagement with the turn table and 95 stop the machine in the well known manner. Should it be desired to discontinue playing 100 of the machine before the stopping point has been reached, this result can be readily accomplished by lifting the tone arm and 105 swinging it outwardly away from the detent member 7. The detent member 7 is preferably curved and segmental in shape, as shown. Owing to the fact that the trip arm is carried by one side of the tone arm, 110 it has a substantially longitudinal movement through the notch 8 when initially setting the device, and the lateral or side stresses are reduced to a minimum, all of which it will be readily understood is conducive to 115 obtaining an accurate and positive operation of the mechanism.

Figures 3 and 4 illustrate an arrangement which can be used when applying the control device as an attachment to electrically driven machines. The brake shoe is,

of course, eliminated, and the control lever is provided with a contact arm 16^a which is arranged for engagement with a contact member 17^a to close the circuit through the electric motor when the control lever is 70 moved against the action of the spring 10. The contact arm 16^a and contact point 17^a are suitably insulated, as indicated at 18, and connected to the electric wires 19. The spring 10 normally tends to swing the control lever 1 upwardly and disengage the contact elements, thereby opening the motor circuit. The motor is thus inoperative at all times except when the control lever 1 is 75 swung downwardly against the action of the spring 10. The manner of setting the device is exactly as previously described, and it will be obvious that the motor circuit will be closed as long as the trip arm 12 is in engagement with the riding edge 7^a of the 80 detent member 7, although the control lever will be swung to open the circuit and stop the motor as soon as the trip arm is brought into registry with the notch 8.

On Figure 5 the invention is shown as applied to a tone arm A' of the Victor type. The construction and manner of mounting of the different parts of the control device is exactly as previously described, although the control lever 1 is shown as provided with a finger piece 20 which is secured to an ear 21 at the upper edge of the detent member 7, and extends across the top of the record in a position substantially parallel to and under the tone arm. The finger piece extends beyond the axis of the control lever, so that when the end of the finger piece is swung upwardly the parts assume the dotted line position indicated by Figure 5 and the brake shoe is moved into inoperative position. The finger piece 20 is arranged in such a manner that the extremity thereof can be readily engaged by one of the fingers of the hand with which the reproducer is grasped to move the same into operative position when starting to play a record. This arrangement enables the entire mechanism to be controlled by a single hand. If desired, a second brake shoe 22 may be suitably mounted upon the outer end of the 100 control lever 1 and arranged to engage the periphery of the turn table E. The two brake shoes 6 and 22 may either be used together or either to the brake shoes may be used independently of the other, any one 105 of the several arrangements being susceptible of producing the desired result.

A slight modification is shown by Figure 6, in which the brake shoe is adapted to be applied by gravity, and the use of a separate element, such as the spring 10 to apply the brake, is avoided. The control lever 1^c is pivotally mounted upon the base plate 4, as previously described, although the arm which carries the brake shoe 6^c is not re- 110 115 120 125 130

turned but is extended in the plane of the lever. The weight of the detent member or wing 7^a at the outer end of the lever, normally tends to tilt the lever to apply the brake and stop the record carrier or turn table. The riding edge 7^d of the member 7 faces downwardly, and the notch 8^e extends upwardly from the lower edge of the member. The positions of these members is thus substantially reversed, and while the phonograph is playing the riding edge 7^d rests upon and frictionally engages the trip arm 12, thereby cooperating with the trip arm to hold the control lever in inoperative position. As soon as the reproducer needle has reached the predetermined point upon the record where it is desired to stop the machine the notch 8^e is brought into registry with the trip arm 12, with the result that the outer end of the control lever 1 drops down by gravity, thereby causing the trip arm to enter the notch and the brake shoe to be applied. The preliminary setting of the device is accomplished substantially as previously described, and a finger piece 20^c may be provided for convenience in manipulating the parts when initially setting the stop. The finger piece extends over the top of the record and under the tone arm, so that it can be readily engaged by one of the fingers of the hand which is used for bringing the reproducer into proper cooperative engagement with the record.

A further slight modification is shown by Figure 9, in which the construction is substantially the same as that shown by Figure 5, with the exception that the notch 8^b is flared downwardly and has a restricted mouth which corresponds substantially in width to the width of the trip arm. This construction of the notch will cause the trip device to be substantially self setting upon depressing the brake when the device is used in connection with a tone arm of the Victor type.

This automatic stop device, while very simple in its construction, has the advantage of being extremely accurate in its operation and of enabling the trip device to be set by a movement of the tone arm in either direction. It is not necessary for the operator to remember that the tone arm must be moved in some special direction when initially setting the device, and neither is it necessary for the operator to learn to set the needle a few grooves inward or ahead of the exact stopping point desired, depending upon the peculiarities of the particular stop involved. The arrangement of the trip arm whereby it is pivotally mounted at one side of the tone arm has the advantage of enabling the pivot point of the trip arm to be removed sufficiently far from the detent device so that there is only a slight variation of the angular relation between the

two members, and this is a feature which is conducive to accuracy in the operation of the stop device. It will also be understood that if it is desired to stop the machine while a record is playing and before the predetermined stopping point has been reached, it is merely necessary for the operator to swing the tone arm beyond the turn table so that the trip finger is moved away from the riding edge of the detent device, whereupon the brake is applied and the turn table or record carrier stopped.

Having thus described our invention what we claim and desire to secure by Letters Patent is,

1. In a graphophone mechanism, the combination with a record carrier and a tone arm having a reproducer to traverse a record on the record carrier, of a control lever, a brake shoe mounted directly upon the control lever, a wing carried by the control lever and formed with a notch and a riding edge leading to the notch, and a trip arm connected with the tone arm so as to be movable therewith and adjustable with respect thereto, said trip arm being adapted to slide upon the riding edge of the wing to hold the control lever in inoperative position during the playing of the record and to enter the notch and permit the control lever to apply the brake when the playing has reached the point where the device has been set to stop the mechanism.

2. In a graphophone mechanism, the combination with a record carrier, and tone arm having a reproducer to traverse a record upon the said carrier, of a control lever, brake means actuated thereby, a finger piece connected with the control lever and overhanging the record carrier for use in manually manipulating the control lever, a trip arm, and a cooperating detent member, one of the said cooperating members being connected with the tone arm while the other cooperating member is connected with the control lever.

3. In a graphophone mechanism, the combination with a record carrier, a tone arm having a reproducer to traverse a record upon the said carrier, and a stopping device for the carrier, of a trip arm movable with the tone arm and adjustable relative thereto, and a detent member operatively connected with the stopping device and formed with a riding edge which is slidably engaged by the trip arm and also with a notch in which the trip arm has an accurate sliding fit, the trip arm being adapted to be set by placing it in the notch and moving the tone arm in either direction until the reproducer is at the point on the record where it is desired to stop the play of the mechanism.

4. In a graphophone mechanism, the combination with a record carrier, a tone arm having a reproducer to traverse a record

- upon said carrier, a control lever for stopping the record carrier, a finger piece connected with the control lever for manually manipulating the same, a trip arm and a 5 cooperating detent member, one of said cooperating members being connected with the tone arm while the other cooperating member is connected with the control lever.
5. In a graphophone mechanism, the combination with a record carrier, a tone arm having a reproducer to traverse a record on the record carrier, a control lever, brake means actuated by the control lever, a finger piece carried by the control lever and extending over the record carrier adjacent the tone arm, so that it can be engaged by one 10 of the fingers of the hand by which the tone arm is grasped, a trip arm and a cooperating detent member, one of the said cooperating members being connected with the tone arm while the other cooperating member is 15 connected with the control lever.
6. In a graphophone mechanism, the combination with a record carrier and a tone arm having a reproducer to traverse a record upon said carrier, of a control lever, brake means actuated by the control lever, a wing rigid with one end of the control lever and provided with a notch and a riding edge 20 leading to the notch, and a trip arm connected with the tone arm, said trip arm being adapted to slide over the riding edge of the detent member and to enter the notch to permit 25 operation of the brake means by the control lever.
7. In a graphophone mechanism, the combination with a record carrier and a tone arm having a reproducer to traverse a record upon said carrier, of a control lever, a base 30 plate upon which the control lever is pivotally mounted, a brake shoe carried by the control lever, an integral upstanding wing at the outer end of the control lever, said wing being transversely disposed with 35 respect to the control lever, and being provided with a notch and a riding edge leading to the notch, and a trip arm connected with the tone arm so as to be movable therewith and adjustable with respect thereto, said trip 40 arm being adapted to slide upon the riding edge of the wing to hold the control lever in inoperative position during the playing 45 of the record and to enter the notch and permit the control lever to apply the brake when the playing has reached the point 50 where the device has been set to stop the mechanism.
8. In a graphophone mechanism, the combination with a record carrier and a tone arm having a reproducer to traverse a record upon said carrier, a base plate having upstanding pivotal ears, a control lever formed of a single piece of sheet material and having a comparatively wide intermediate 55 portion which is pivotally mounted between the before mentioned ears of the base plate, one end of the control lever being reduced and returned, an integral upstanding and transversely disposed wing at the opposite end of the control lever, a brake shoe carried by the returned end of the control lever, the upstanding wing being formed with a notch and a riding edge leading to the notch, and a trip arm connected with the tone arm so as to be movable therewith, said trip arm being adapted to slide over the riding edge of the wing and to enter the notch to permit 60 of the movement of the control lever into position to apply the brake.
9. In a graphophone mechanism, the combination with a record carrier and a tone arm having a reproducer to traverse a record upon said carrier, of a stopping device for the carrier, a detent member connected with the stopping device and formed with a notch and a riding edge leading thereto, and a trip arm connected with the tone arm at one side thereof, so that it extends substantially parallel with the tone arm but is off-set therefrom, said trip arm being adapted to 65 slide upon the riding edge of the detent member and to enter the notch to permit functioning of the stopping device.
10. In a graphophone mechanism, the combination with a record carrier and a tone arm having a reproducer to traverse a record upon said carrier, of a stopping device for the carrier, a detent member connected with the stopping device, a bracket arm projecting from the tone arm, and a trip member 70 carried by the bracket arm, one of said members being returned to receive the other, and pivot means frictionally connecting the returned member with the other member.
11. In a graphophone mechanism, the combination with a record carrier and a tone arm having a reproducer to traverse a record upon said carrier, of a stopping device for the carrier, a detent member connected with the stopping device, a bracket arm projecting from the tone arm, a trip arm carried by the bracket arm, one of said arms being resilient and being returned to receive the other arm, and a pivot member adjustable in the returned arm and cooperating with 75 the resilient action thereof to produce a frictional connection between the arms.
12. In a graphophone mechanism, the combination with a record carrier and a tone arm having a reproducer to traverse a record upon said carrier, of a stopping device for the carrier, a detent member connected with the stopping device, a bracket arm projecting from the tone arm, a trip arm carried by the bracket arm, one of said arms being resilient and being returned to receive the other arm, a screw adjustably threaded in the returned arm, and a member interposed between the end of the screw and the other arm for cooperation with the screw to obtain 80

a frictional pivotal connection between the arms.

13. In a graphophone mechanism, the combination with a record carrier and a tone arm having a reproducer to traverse a record upon said carrier, of a stopping device for the carrier, a detent member connected with the stopping device and formed with a notch, and a riding edge leading to the notch, said notch having an enlarged inner portion and a contracted mouth, and a trip arm connected with the tone arm and adapted to slide over the riding edge of the wing and to enter the notch to permit movement of the control lever to actuate the electric switch.

14. In a graphophone mechanism, the combination of a record carrier and tone arm having a reproducer to traverse a record upon said carrier, of a control lever, an electric switch actuated by the control lever for stopping the record carrier, an upstanding wing rigid with the control lever

and formed with a notch and a riding edge leading to the notch, and a trip arm connected with the tone arm and adapted to slide over the riding edge of the wing and to enter the notch to permit movement of the control lever to actuate the electric switch.

15. In a graphophone mechanism, the combination with a record carrier and a tone arm having a reproducer to traverse a record upon said carrier, of a stopping device for the carrier, a detent member connected with the stopping device, a bracket arm projecting from the tone arm, and a trip arm having a frictional pivotal connection with the bracket arm, whereby it can be swung into different adjusted positions with respect to the tone arm, said trip arm being mounted in cooperative relation to the detent member.

In testimony whereof we affix our signatures.

CLIFFORD C. BROOKS.
EDWIN O. KLEMM.
